Primary Examiner — Ian Simmons*Assistant Examiner* — Keith Frank(74) *Attorney, Agent, or Firm* — Andrus Intellectual Property Law, LLP(57) **CLAIM**

The ornamental design for a dumbbell, as shown and described.

DESCRIPTION

FIG. 1 is a front perspective view of a dumbbell showing my new design;

FIG. 2 is an end view thereof.

FIG. 3 is an opposite end view thereof.

FIG. 4 is a front view thereof.

FIG. 5 is a rear view thereof.

FIG. 6 is a top view thereof; and,

FIG. 7 is a bottom view thereof.

The broken lines in the drawings showing the dumbbell illustrate the portions of the dumbbell that form no part of the claimed design.

1 Claim, 4 Drawing Sheets(56)
